WILLIAM L. DEMING AND CHARLES CORNWALL, OF SALEM, OHIO, ASSIGNORS TO THE DEMING COMPANY, OF SALEM, OHIO, A CORPORATION OF OHIO.

SPRAYING DEVICE.

1,348,631.

Specification of Letters Patent.

Patented Aug. 3, 1920.

Application filed January 20, 1919. Serial No. 271,977.

To all whom it may concern:

Be it known that we, WILLIAM L. DEMING and CHARLES CORNWALL, both residing at Salem, in the county of Columbiana and State of Ohio, have invented certain new and useful Improvements in Spraying Devices, of which the following is a full, clear, and exact description, reference being had to the accompanying drawings.

10 This invention relates to a nozzle structure for use in spraying trees, plants, buildings, etc., where the nozzle is directed by hand. The object is to provide a simple and efficient device readily held by the operator 15 and easily adjusted for different forms of spray. Devices of this general character and having a tubular barrel adapted to be secured at the end of a hose are called in trade "spray guns". They are very useful in spraying insecticide upon trees, for instance. In such use the fineness of the spray is varied during the operation according to whether one is spraying the lower leaves or 20 those near the top of the tree, the range of this variation extending from a fine spray 25 to substantially a solid stream. Our invention provides for this adjustment in a very simple and effective manner without rendering the parts cumbersome.

30 In spraying with poisonous insecticide or discoloring liquid it is particularly desirable that the liquid which drips from the nozzle should not come in contact with the operator's hands. Our nozzle may readily 35 carry a shield preventing such dripping liquid to cause any inconvenience and maintaining the nozzle portions beneath the shield dry so that they may be satisfactorily grasped by the operator in making the adjustment.

40 The body portion of our spraying nozzle has a tubular member closed at its end and provided with a lateral orifice and an external thread, and combined with this is a 45 sleeve member having an internal thread and an unthreaded annular recess and a central discharge orifice. With such an arrangement the internal thread of the sleeve may serve to give the liquid a whirling motion 50 to cause it to be emitted in the form of a spray, or by reason of the unthreaded recess the liquid may discharge over the end of the central body without being acted on by such thread, and thus continue as a solid stream. 55 These results and various intermediate

grades of spray may be effected by varying the longitudinal position of the sleeve member on the body member, this variation being effected by a screw-threaded connection between these parts, enabling the turning of 60 either member relative to the other to change their longitudinal position. The inward movement of the sleeve member on the body is limited by the closed end of the body abutting the inner face of the head portion of 65 the outer member. Such abutment has the effect of entirely closing the nozzle, shutting off the discharge altogether.

Our invention comprises a very simple, and effective construction and arrangement 70 of parts embodying features just explained. It also includes an extended sleeve surrounding the pipe portion of the device, and providing means for turning the sleeve to adjust the nozzle. Our nozzle structure 75 consists of a few parts which are cheaply made and readily assembled.

Our invention will be more apparent from the description of a satisfactory embodiment thereof illustrated in the drawings hereof. 80 In these drawings, Figure 1 is an axial section of our spraying device, the nozzle being shown closed. Fig. 2 is an enlarged axial section of the discharge portion of said device, the parts being in a position to discharge a spray; Fig. 3 is a similar view to Fig. 2 showing the nozzle in position to discharge a solid stream; Fig. 4 is an end view of the spray gun; Figs. 5 and 6 are cross sections, as indicated by the corresponding 85 numbered lines on Fig. 3.

As shown in Figs. 1, 2 and 3, 10 indicates the tubular body or stem of our spraying device. This is a pipe of any desired length. At its inner end it is threaded into a tubular 95 casing 11, having its exterior fluted to enable it to be conveniently grasped and turned by the hand. This hand hold preferably flares and has at its other end an internal thread 12 adapted to screw onto the pipe or hose 100 from the spray pump or other source of supply.

Secured to the outer end of the stem 10 is a head 20, shown as a cap surrounding the stem and rigidly secured to it. This cap has 105 on its exterior a square thread 21 and we thus thread a cylindrical extension terminating in a flat disk-like head 22 closing the end of the cap. Between the thread and this disk-like head are lateral discharge orifices 24, 110

preferably radial, six being shown leading from the end of the stem 10, outwardly to the exterior of the cap.

Surrounding the stem 10 and head 20, is shown a tubular sleeve 30 having two internal square threads 31 and 32 separated by a recess 33. The two sets of threads are parts of the same helix so that the externally threaded head may screw continuously from the thread 31 to the thread 32, notwithstanding the intermediate recess.

On the outer side of the sleeve 30 is shown a thread 35. Onto this screws a cap 40 having a central opening 41. This cap operates to clamp a disk 42 with a small central opening and a rubber packing washer 44 against the end of the sleeve. Between the cap and the thread 32 a chamber 36 is formed in the end of the sleeve.

With the construction described, if the parts occupied the position shown in Fig. 3, the liquid coming through the stem 10 discharges laterally through the orifices 24 into the recess 33 and thence passes inwardly over the end of the head 20 and centrally out of the discharge orifice in the form of a solid stream. If, however, the sleeve is turned further onto the stem until the disk head 22 extends into the opening within the thread 32, the liquid discharged through the passageways 24 can only reach the central discharge orifice by means of the oblique passageways 34 provided by the thread 32. This gives a whirling motion of the liquid in the chamber 36, causing it to be emitted in the form of a spray, as indicated in Fig. 2.

Fig. 1 indicates the position of the parts when the sleeve has been screwed onto the body into its extreme position. In this position the head 22 abuts the elastic washer 44 and the discharge is entirely shut off.

To make a connection between the sleeve member and the stem which shall be liquid tight and at the same time allow movement of the sleeve, we provide a stuffing box consisting of a sleeve nut 50 screwing into an internally threaded extension 38 of the cap body and operating to compress packing rings 51 against an internal shoulder 39 in the sleeve. The screwing in of the sleeve nut 50 compresses the packing sufficiently to make a liquid tight connection between the sleeve and the stem 10, this connection preventing any displacement of the sleeve and at the same time enabling it to be turned when desired to shift it longitudinally on the body 20 and thus vary the kind of stream thrown.

It will be seen that the construction is simple and at the same time effective. With the thread shown less than one rotation of the sleeve carries it from its extreme inner position, shown in Fig. 1, to its extreme outer position, shown in Fig. 3. The outer position is limited by the sleeve shoulder 39 abutting a ring 55 secured to the stem 10. In

this position the orifices 24 discharge into the recess 33 and there is sufficient clearance over the head 22 for this liquid to then pass unobstructed into the cavity between the head 22 and the discharge opening, the discharge being accordingly a solid stream.

If the sleeve be given a portion of a rotation from the position shown in Fig. 3, it is brought into the position shown in Fig. 2 where the orifices 24 may discharge into the recess 33, but the direct discharge from the recess is closed by the head 22 occupying the central space surrounded by the thread 32. The oblique thread grooves being the only means of exit for this liquid it takes such path and is thereby given a whirling action, causing the discharge in the form of spray. If the sleeve be given a still further turn for a portion of a rotation it is brought into the position shown in Fig. 1, where the elastic washer 44 abuts the flat head 22 and the discharge from the nozzle is shut off.

The body of the sleeve member 30 is of sufficient extent to provide a very convenient hand hold for turning this sleeve. The exterior of this body is preferably fluted, as shown at 36, to enable it to be conveniently grasped adjacent to the end of the device. In order that the sleeve portion 30 may be given its adjusting rotation without requiring the operator to reach out and take hold of the sleeve itself we provide a tubular extension 60 which surrounds the stem 10 and extends any suitable distance along this stem and is secured at its outer end to one of the rotative parts of the nozzle. We find it very convenient to secure this extension tube 60 directly to the stuffing box nut 50. As shown, the stuffing box nut has an angular groove in its end which is entered by the tube, the parts being preferably brazed or pinned together. Independent rotation of the stuffing box nut and the sleeve may be prevented by any suitable means, as a set-screw 65 mounted in an ear 66 on the sleeve and bearing against an annular shoulder 67 of the stuffing box nut. The extension sleeve 60 is preferably formed into flutes 61 or otherwise knurled near its lower end to enable it to be conveniently grasped. 63 indicates a bushing set into the end of this extension sleeve and providing a convenient bearing on the stem 10.

The construction just described enables the nozzle to be adjusted either by the operator grasping the sleeve 30 or the extension tube 60. In either case his hand is protected by the rubber shield 70. This is shown as an annular disk-like member beaded at its periphery and also about a central opening. The central opening is of such size that the rubber shield may snugly surround the body of the shield adjacent to the threads 35. This shield is put in place 130

when the cap 40 is removed and is held between the inner end of that cap and a shoulder 37 on the exterior of the sleeve.

It will be noticed from the drawing that 5 the threads on the plug and cap are of steep pitch, being preferably a double thread, as shown. This not only enables the desired longitudinal adjustment by a comparatively small amount of turning, but also gives a 10 better direction for the whirling liquid as it enters the chamber 36, the steep spiral discharge of this liquid giving the necessary whirling to the body of liquid in the chamber, and at the same time rapidly progressing it to the discharge orifice. Moreover, the double thread gives two spiral entrances diametrically opposite to the chamber. We have found that this double entrance of the square thread groove of steep 15 pitch produces a very satisfactory result.

It will be seen that our construction is very simple. It may be readily cleaned, the removal of the cap 40 allowing the sleeve to be screwed past the head 20 and slid 20 down along the stem until the head 20 is entirely exposed. This provides access to the passageways 24, enabling any obstruction therein to be removed. The threads and adjacent parts may also be readily cleaned 25 when thus separated. The packings, both for the stuffing box and at the head of the nozzle, are readily replaceable when necessary. To further vary the fineness of the spray the disk having the discharge orifice 30 may be removed and another disk with a different sized hole substituted.

Having thus described our invention what we claim is:—

1. In a nozzle, the combination of a tubular stem, having an external thread of 40 greater diameter than the unthreaded portion, and a sleeve member having an orifice and an internal thread of uniform pitch which engages the external thread of the 45 stem, there being a lateral opening from the stem adapted to discharge independently of the internal thread or through a portion of it according to the relative position of the sleeve and stem, and there being a 50 chamber for whirling fluid of substantially the diameter of the threads with which the thread groove of the sleeve member communicates.

2. In a nozzle, the combination of a tubular stem having an external thread near 55 one end and a head beyond the thread, a sleeve member having a coöperating internal thread of uniform diameter and pitch, a recess intermediate the ends of the thread, and a lateral passageway through the stem adapted to direct liquid to said recess.

3. In a nozzle, the combination of a sleeve member having a discharge orifice, a chamber, and an internal multiple thread providing a plurality of spiral grooves entering

the chamber, and an internal stem having threaded engagement with said sleeve thread and having a closed end and a lateral passageway adapted to discharge fluid into the chamber, whence the fluid may pass in a 70 stream directly through said orifice, or be whirled by said internal thread and emitted through said orifice as a spray, or its flow checked entirely, in sequential order as the stem and sleeve are moved relatively along 75 said threads to bring said closed end against said orifice.

4. In a nozzle, the combination of a stem having an external multiple thread and a closed end, a sleeve member having a discharge orifice, a chamber and an internal multiple thread adapted to engage said external thread providing a plurality of spiral grooves entering the chamber, and radial passageways through the stem between its 80 thread and head and adapted to discharge fluid to be whirled by the internal thread.

5. The combination of a tubular stem having a head and an external multiple thread, a sleeve member having a discharge orifice 90 and having a chamber adjacent thereto and having an internal thread complementary to said external thread, part of which internal thread normally engages said external thread and part of which is out of such engagement, there being lateral radial openings through the stem adapted to communicate with the passageways provided by the unoccupied internal thread.

6. In a nozzle, the combination of a tubular stem having an external thread near one 100 end, a head beyond the thread, a sleeve having an internal thread engaging the external thread of the tubular stem, said internal thread having an annular recessed portion 105 between its ends, a stuffing box carried by the sleeve and adapted to engage the wall of the tubular stem, and a lateral opening from the stem for liquid which may be discharged by passing into said recessed portion and 110 through a portion of the helical groove provided by said internal thread.

7. In a nozzle, the combination of a tubular stem of substantially uniform diameter through its length, a head secured over the 115 end of the stem and closing it except for lateral passageways, and having an external thread thereon, a surrounding sleeve having an internal thread adapted to mesh with said external thread, the sleeve having an 120 opening in the end, and being provided with means for whirling the liquid discharged through said lateral passageways, and a stuffing box engaging the sleeve and the stem.

8. The combination of a tubular stem having a flat head at its end, an external thread about the stem, and lateral discharge openings through the stem between the head and thread, a sleeve member having a coöperat- 130

ing internal thread, said internal thread having a portion of the helical wall intermediate its ends removed, and a washer at the end of the sleeve member which said head is 5 adapted to engage by adjustment.

9. The combination of a tubular stem having a flat head at its end, an external thread about the stem, and lateral discharge openings through the stem between the head and thread, a surrounding sleeve having an internal thread meshing with the thread mentioned, a cap screwing onto the external sleeve, and a disk having a small opening and a packing washer held by the cap 10 15 against the external sleeve, and projecting inwardly far enough to be engaged by said head when the sleeve is screwed to its limit onto the stem.

10. The combination of a tubular stem, a 20 cap thereon having a head and an external thread, a lateral passageway through the cap between the head and thread, a sleeve screw threaded on said thread, the threaded portion of the sleeve opposite said passageway having an annular recess, the portion of the thread on one side of the recess being a 25 continuation of that on the other and both portions being adapted to act with said external thread, a central bore in the head communicating with said recess, and a chamber 30 in the sleeve beyond the threaded portion, said threaded portion forming an oblique

passageway in the sleeve from the recess to said chamber.

11. The combination of a tubular stem 35 provided with a head and an external thread and a lateral passageway between the head and thread, a sleeve screw threaded on said thread, a recess in the sleeve opposite said passageway, a central bore in the sleeve 40 communicating with said recess, a chamber in the sleeve beyond the central bore, a helical groove in the body of the sleeve at the edge of the central bore forming a continuation of the screw threaded helix of the 45 sleeve, and a cap on the sleeve and having a discharge orifice.

12. In a nozzle, the combination of a tubular stem having an external thread near one end and a head beyond the thread, a sleeve 50 member having a coöperative internal thread and a chamber intermediate the ends of the thread, the thread on one side of the chamber being a continuation of the helix of the thread on the other side, the outer portion of said internal thread providing an oblique opening between said chamber and the discharge end of the sleeve, and there being a lateral passageway through the stem 55 adapted to direct liquid to said chamber. 60

In testimony whereof, we hereunto affix our signatures.

WILLIAM L. DEMING.
CHARLES CORNWALL.
